UNITED STATES PATENT OFFICE

EDWARD E. KLEINSCHMIDT, OF CHICAGO, ILLINOIS, ASSIGNOR TO TELETYPE CORPORATION, OF CHICAGO, ILLINOIS, A CORPORATION OF ILLINOIS

SELECTIVE SIGNALING AND APPARATUS

Application filed April 16, 1928. Serial No. 270,389.

My invention relates to selecting and printing mechanism, and more particularly, the invention relates to printing telegraph mechanism.

5 In high speed printing telegraphy, the rate at which signals can be transmitted has heretofore usually been greater than the speed at which the printer can be operated. This is due to the number of operations which 10 must be performed by the printer following the receipt of a code combination of impulses. Thus for example, the selecting apparatus must first function in response to these impulses to select a character for a 15 printing operation. Thereafter the selected character is positioned for printing, the printing hammer is operated, and letter and line spacing are some among many other operations which must take place before the 20 printer is in condition for a succeeding code. It is evident from this, that ordinarily an interval of time must elapse between the receipt of the last impulse of a code and the first impulse of the succeeding code to provide 25 sufficient time to permit the above described printing operations to take place.

This is undesirable as it slows the speed at which messages may be transmitted and decreases the efficiency of the signaling line 30 in handling traffic considerably inasmuch as for considerable periods of time, the line is idle. In order to utilize all of the signaling line time available, overlap devices have been provided, as is well known in the art, 35 by means of which impulses are received on a first selector and transferred to a second selector. Printing operations occur as a result of the selection set up on the second selector while the first selector responds to a 40 succeeding code combination of impulses. Inasmuch as the first selector transfers its setting simultaneously to the second set near the end of a signaling period, it is immediately 45 free for a new setting and accordingly the full line period is available for use. Since the setting of the first set of selectors is transferred to the second set of selectors simultaneously the printing operations may occur almost immediately thereafter, permitting thereby substantially the full signal-

ing period for printing operations while the first set of selectors are responding to the succeeding code combination of impulses.

Heretofore those of the first set of selectors which have been operated in response to the code of impulses have been latched in operated position in preparation for the subsequent transfer operation at the end of the signaling period. Latching selectors has been necessary inasmuch as they usually 55 have a normal non-operating position in which they remain in response to a spacing impulse and an operated position to which they are moved in response to a marking impulse, each selector returning to its normal 60 spacing position when released or unlatched in response to spacing signal. In some cases, these selectors are arranged to remain in their operated positions after their setting 65 has been transferred to the overlap or second 70 selectors, the succeeding code functioning either to latch those selected bars entering the new combination which were not part of the preceding combination and releasing those latched selectors operated by 75 the preceding combination, but which do not enter the new combination. In another arrangement, the latched selectors are restored to normal after each transfer operation. In both cases, however, it will be observed, the selectors are operated only by 80 marking impulses, the spacing impulses either having no effect or merely unlatching operated selectors to permit a return to normal. Latches, however, have been found to 85 add complexity to the telegraph apparatus to increase the power required for operations and to slow the speed of operation.

Accordingly, an object of my invention is to provide a printing telegraph apparatus 90 with a complete overlap in which the selectors are not latched in operated position.

A further object of my invention is to provide an overlap selector arrangement in which the selectors responsive to the received impulses have no normal position.

In the operation of stock tickers, the number of letters and numerals printed in the course of the usual operation are approximately evenly divided and it has accord- 100

ingly been found desirable to employ separate letter and numeral typewheels with a sixth impulse for the shift operation to select either the letter or numeral typewheel. Although an overlap is essential as pointed out above, for the selection operation, it is clear that since the shift operation occurs just before printing, that a direct connection from the first set of selectors operating in response to the sixth impulse to the shift mechanism can be made eliminating the need of an extra overlap selector for this operation. Alternatively, the switch over operations may at the same time function to select the typewheel.

A further object of my invention is to provide printing telegraph apparatus in which selective operations are made with an overlap selector in which the shift selection occurs, simultaneously with the switch over operation.

Where high speed operations are desirable, it is of prime importance that the typewheel be released for rotation to a selected position as soon after the transfer to the second set of selectors occurs as possible. Heretofore, this has been accomplished by a timing mechanism which releases the typewheel after an interval of time following the selecting operation transfer. Since, however, as soon as the selection is transferred to the second selectors, a new selected position is immediately made, it is clear that the typewheel may be released simultaneously with this movement of the selectors.

A still further object of my invention is, therefore, to provide a typewheel printer in which the movement of the overlap selectors to a new selected position automatically releases the typewheel for movement to the new selected position.

The rotating typewheel when brought to a stop has been found to have a tendency to rebound and chatter at the stop position due to the jar or shock caused by bringing a typewheel rotating at high speed to a sudden stop. This causes blurring of the printed character as the printing hammer is brought into engagement with the chattering typewheel. In order to prevent this rebound of the typewheel, a latching spring is provided as part of the typewheel stop arm which latches in front of the stop pin when the stop arm comes to a stop.

Accordingly, a still further object of my invention is to provide a stop arrangement in connection with a typewheel for preventing chattering or rebound of the typewheel.

As is well known, stock tickers are operated in systems over which the signaling traffic varies over a very wide range from a heavy to very light traffic. It is accordingly desirable that a flexible control of the printing apparatus in such a system be provided so as to permit ease in starting-up and

stopping of the motor controlling the printer. To accomplish this, it has been necessary heretofore to provide special line equipment for such operations. This, however, adds unnecessary complications and costs to the system.

A still further object of my invention is, therefore, to provide a simple printing telegraph selector which controls the printing telegraph motor.

Further objects of the invention are such as may be attained by the utilization of the various combinations, sub-combinations and principles hereinafter set forth and as are defined by the scope of the appended claims.

Figure 18 is a transverse sectional view of Figure 17, and

Figure 19 is a sectional view through the slip clutch in Figure 1.

In Figures 1 and 2 the mechanism controlled by a single selector magnet which may be of any well known construction especially designed for use in stock ticker operations is mounted on a frame work 1 which carries the magnet 2. Supported on the

core 3 are the magnet windings 4 and pivotally supported from the permanent magnet is the oscillating armature 5, the motion of which is limited by means of the adjustable 5 stop screws 6. The twisted extension 7 of the armature 5 extends between the two shoulders 8 and 9 on the selector cam shaft extension 10. The cam shaft extension 10 is formed integrally with the shaft 11 and is 10 slidably journaled in a stationary bearing 12 which is supported from the frame work as shown. Shaft 11 comprises a flat stamped metal member with six pairs of oppositely disposed fingers 13. The flat 15 stamped metal member is twisted as indicated in Figures 1 and 2, disposing the fingers 13 in angular relation about the longitudinal axis of the shaft.

The shaft 11 extends through a rotatable 20 hollow shaft member 14 suitably journaled in the framework and secured to the end of shaft 11 is the friction member 15 of the slip clutch described fully hereinafter. Pivoted to shaft 11 at 17, adjacent 25 the end of shaft 14 is a driving member 18 whose opposite end operatively engages shaft 14 whereby rotation of shaft 14 is transmitted to shaft 11.

Mounted on and secured for rotation with 30 shaft 14 is a star wheel 19 the cam shaped periphery of which actuates a bell crank lever 21 (Figure 3) pivoted at 22 to the framework. Bell crank 21 rocks a pivoted arm 23 (Figure 2) about its pivot 24 moving 35 the locking lug 25 carried thereon out of and into the path of the armature extension 7. The lug on pivoted lever 23 is normally held by the spring 26 in the path of armature extension 7. The cam projections 40 on the star wheel 19 are so shaped that the lever 23 is rocked in a clockwise direction through bell crank 21 to remove the lug 25 from the path of armature extension 7 releasing it for operation in response to a received 45 impulse during the mid portion of signaling period. Immediately thereafter, however, the bell crank 21 is rocked in the opposite direction by the cam projections on the star wheel 19 and rocks the lever 23 50 counter clockwise moving lug 25 into engagement with the armature in its operated position. In this manner the armature is free to respond only to the peak portion of each impulse and is locked during the 55 remaining portions thereof preventing chattering of the armature during the transient periods of such impulses.

Slip clutch 16 comprises in addition to the member 15, a surrounding open ended cylindrical member 27 in which the ends of friction contact springs 28 are secured, the intermediate portions of which frictionally engage member 15 as indicated in Figure 19. Secured in member 27 is one end of a shaft 60 29 supported from the frame work by anti-

friction bearings 31, the opposite end of which is supported in bearing 31' suitably supported from the frame. Secured to and rotatable with shaft 29 is a spiral gear 32. Shaft 29 is driven continuously while the printer is operated through spiral gear 32 meshing with worm 33 carried by and rotatable with main drive shaft 34. The power is transmitted through clutch members 16 and 15 to the extension 14 of shaft 29 which, however, is latched against rotation as will be described hereinafter. Clutch member 15 therefore slips on rotating springs 28 at this time. Provision is made in the bearings 31 and 31' to take up the thrust due to the fact that the shafts 29 and 34 operate at right angles to each other. It will be understood that this drive may be effected with bevel gears if so desired.

A stop member 35, Figures 1 and 9, carried by shaft 11 normally engages a lug 36 carried by an orienting plate 37 which is rotatably mounted on shaft extension 14 and rigidly held by securing means 38 in a manner to permit its adjustment about the shaft extension as a center. An orienting portion 37 is provided for adjusting the relative position of the stop member 36 which is rigidly held in its set stop position. As shown in Figure 1 when the armature 5 of the magnet 2 is attracted, the shaft 11 is in zero or normal position. When the magnet is deenergized, shaft 11 is moved longitudinally to the right and stop arm 35 disengages lug 36 releasing the shaft 11 to be driven by rotating shaft 29 through clutch 16.

It will be recalled that the six pair of fingers 13 are spaced angularly around the shaft 11 as a result of the twisting of shaft 11. As shown in Figures 5, 6 and 9, as the cam shaft 11 rotates, each of the fingers 13 will successively engage the cam portions 41 and 42 of wish-bone selector levers 43, individual to each pair of fingers. Each of these wish-bone selectors 43 pivoted for rocking movement on the stationary supporting rod 44, are provided with arms 45 and 46 each having a cammed portion 41 and 42 arranged in the path of their individual fingers and engaged thereby as the latter rotate.

Each of the fingers are as described above, divided into pairs, each pair being arranged diagonally opposite each other on the shaft 11. When the shaft is moved longitudinally in response to a marking impulse, the cammed surface of one of the fingers 13 will engage the cam portion 42 of the arms 45 and will, as a result, rock its individual wishbone selector counter-clockwise. Simultaneously, the diagonally opposite finger 13 rides in front of the arm 46 of the wishbone selector which has now been rocked to

130

its operated position. It will be clear that as this finger moves in front of arm 46 the shaft 11 is locked from further operation during the remainder of the impulse period. 5 If on the other hand, a spacing impulse is received, the cam portion of the finger 13 engages the sloping portion 41 on the right side of the wishbone selecting lever while at the same time the diagonally opposite 10 finger rides in front of the wishbone selecting lever thereby locking the shaft 11 from further operation by the receiving magnet during this impulse period. In this manner, as soon as a selector 43 is operated, the shaft 15 11 is locked against longitudinal movement as a result of the movement of the selector to operated position through the second of the pair of fingers.

It is clear from this description, therefore, 20 that not only is a lock provided for the armature 7, which, it will be recalled, is locked by lug 25 to prevent its operation except during the mid-portion of the signal impulse period, but in addition the cam shaft 25 11 is locked following each operation of a selector. A double lock is thus provided insuring positive and accurate operations of the selector.

These selectors 43, it will be noted, are 30 not latched in position, in fact, have no normal position but remain set in either of its two operated positions to one of which they move in response to a marking impulse and to the other of which they move in response 35 to a spacing impulse.

In the event that the wishbone selector 43 rocked counter-clockwise about its pivot 44, in accordance with a marking impulse, does not enter into the next code combination 40 of impulses received, the cam portion 41 is engaged by the alternate finger 13 of the pair and the selector is rocked clockwise to its spacing position. It will be clear from this that a simple selecting arrangement is 45 provided in which no latches are necessary as the selecting levers 43 when operated to either of their selected positions remain set until again operated to a different position in accordance with a new code combination 50 of impulses and will, on the other hand, remain in such position in the event that the same selecting lever enters in the same relation in the succeeding code combination of impulses received.

55 In operation of the mechanism so far described, the main shaft 34 rotates continuously driving the worm 33 continuously. Worm 33 in turn drives gear 32 and through clutch 16, the shaft 11. When no signals are 60 being received the position of the parts is such that the arm is engaging the fixed lug 36. The shaft 11 is held from rotation and member 15 slips relative to member 27.

65 The signals to which the mechanism is responsive comprise a start condition, a com-

bination of selecting conditions and a stop condition. The stop condition is normally on the line holding the parts in the position shown in Figures 1 and 2. When a start condition is received the polarity of current flowing through the winding is reversed thereby reversing the magnetic field and causing the armature extension 7 to tilt.

Tilting of the armature 7 in response to start conditions, shifts the cam shaft 11 end-wise so that that stop 35 disengages lug 36, and the friction clutch 16 becomes effective to drive the cam shaft 11 at a speed which is definitely timed with respect to the incoming impulses. In the arrangement shown, the first impulse of the signal following the start condition is received just before the first finger 13 reaches its individual wishbone selector 43. If this first impulse is a marking signal, the armature 7 will be actuated shifting the shaft 11 longitudinally to position the finger 13 to engage the sloping portion 42 of the wishbone selector, rocking the latter about its pivot 44 in a counter-clockwise direction. If on the other hand, the impulse immediately following the start impulse is a spacing signal, the selector magnet 2 will operate its armature 7 in the opposite direction and the finger 13 will ride over the cam surface 41 of the wishbone 43 rocking it a clockwise direction about its pivot. Similarly, each of remaining wishbone selectors are positioned by individual fingers in accordance with the received code.

Each of the wishbone selectors 43 is provided with extensions or prongs 51 and 52. Disposed adjacent these prongs are the lug portions 53 and 54 of the transfer selectors 55. A transfer selector 55 is provided for each of the wishbone selectors 43 and as shown, are pivotally mounted on the pin 56 carried by a transfer lever 57, Figure 4. As will be described in detail hereinafter, the pin 56 is moved toward the wishbone selectors carrying all the transfer selectors simultaneously into engagement with their associated wishbones for operation thereby in accordance with the setting of the selectors 43.

Transfer lever 57 is carried between prongs 58, Figure 1, on shaft 59 mounted in a bearing depending from the frame structure at 61. A lever arm 62 is secured to the end of and rotates the shaft 59 and carries a follower 63 which rides in a cam 64, Figures 1 and 4. Cam 64 is carried on and rotatable with outer shaft 65. Shaft 65 carries a grab clutch 66 normally held out of engagement with clutch 67 by a lever arm 68 riding on the cammed surface 69 of cam member 70 secured to and rotatable with the grab clutch 66. Grab clutch 66 is operatively connected to outer shaft 65 by means of an integral lug 71 extending therefrom and movably engaged within a slot 72

in outer shaft 65. A coil spring 73 is interposed between cam 64 and cam 70 for pushing the clutch member 66 into driving engagement with clutch member 67. The lever 68 is secured to a connecting rod 74 by means of screw 75. Connecting rod 74 carried by a bearing 76 is secured at its opposite end to a lever arm 77. The lever arm 77 is provided with a follower 78 which rides over a cam 79 carried by and rotating with the shaft 14.

As the shaft 11 rotates, the wishbone selectors 43 are set in accordance with the received code as described above. Thereafter, the follower 78 slides over the cam 79 on shaft 14 and rocks the lever 77. Rod 74 is rotated and in turn rocks the lever 68 from under the cammed surface 69 of the cam member 70. Thereupon helical spring 73, one end of which presses against the grab clutch 66, forces it into engagement with the teeth on clutch 67. Clutch member 67 is carried by collar 81 detachably secured to gear 32 by screw 82, and rotatable with the gear 32. The collar 81, therefore, is normally rotating as power is transmitted therethrough from the main drive shaft 34. As soon as the grab clutch 66 engages the teeth of clutch member 67, the outer shaft 65 is driven from the main shaft 34.

As was described above, cam 64 rotates with the outer shaft 65 and rocks the lever arm 62 which in turn rotates the shaft 59 through a predetermined angle. The transfer lever arm 57 carried by shaft 59 is in turn rocked and moves the shaft 56 and the selectors 55 carried thereby towards the wishbone selectors 43, as shown by a comparison of Figures 5 and 6.

As will now be clear from the above description, after the cam shaft 11 has rotated through a sufficient angular movement to position all of the selectors 43 in accordance with the received code, the operated ones of which are moved counter-clockwise. The outer drive shaft 65 is released for rotation under control of a cam 79 on shaft 14, and cam 64 on the outer drive shaft 65 in turn rocks the lever 62. The shaft 59 is rotated and lever 57 carried on the end of the shaft rocks the shaft 56 forward bringing either lug 53 or 54 of each of the selector levers 55 into engagement with their associated lugs 51 and 52 on the pivoted wishbone selectors 43 depending upon whether these selectors are in operated or non-operated position. For example, if the selector 43 is in the position shown in Figure 6, the lugs 51 and 53 engage and as the selector 55 moves downward, it will rotate about its pivot 56 in a clockwise direction. If on the other hand, the selector 43 is in its non-operated position, the lug 52 will engage with lug 54 and the selector 55 will be rocked in a counter-clockwise direction about its pivot

56. It will be noted that this transfer occurs simultaneously for all the selectors 43 and accordingly a complete overlap is thus provided between the selectors 43 and transfer selectors 55, although neither of these are latched in operated position. This transfer operation occurs at a fixed period in the cycle of operations determined both by the release of the outer shaft 65 by means of cam 79 and by cam 64 on the outer shaft. By providing outer shaft 65 to carry cam 64 through which this transfer operation is made, a greater amount of power is available than if the cams for the transfer were carried on shaft 29. Shortly after release of clutch 66, lever 68 is restored to the position shown and at the end of the revolution of shaft 65 cams clutch 66 out of engagement with clutch member 67 bringing the outer shaft to a stop at the end of the revolution.

Projections 85, Figures 5 and 6, on each of the selectors 55 are positioned in slots 86 of individual notched selector disks 87. Disks 87 are rotatably supported on a sleeve 88 Figure 1, which is supported in framework and are disposed between guiding comb plates 89 and 90. Each of the disks 87 are provided with V-shaped notches 92 cut about their periphery in a manner well known in the art. Arranged about the circumference of the disks 87 and guided in slots formed in the guides 89 and 90 are a series of stop members 93 provided with cam rollers 94 which are positioned between guide combs 89 and 90. The stop members 93 are spring pressed inward forcing the rollers 94 into the aligned slots of the disks. In the preferred embodiment of the invention, spring pressure is furnished by the spring members 95 and 96. It will be understood, however, that the members themselves may be constructed of spring wires, for this purpose.

Each transfer selector 55 as it rocks about pivot 56 will turn its associated selector disk 87 to either of its two operated positions. As the selector disks 87 are positioned by the selectors 55 through extensions 85, a predetermined combination of the V-shaped notches will be moved into alignment in the well known manner and a stop member 93 which is opposite the aligned notches will then move into the aligned position.

Journalled in the sleeve 88 is a typewheel shaft 97 which has secured thereto a stop member 98, of such length as to normally miss the non-selected stop members 93 as member 98 rotates with the typewheel shaft. A selected stop member 93 which has dropped into the aligned slots is, however, in the path of stop arm 98. As the latter rotates, it will engage this stop member. The typewheel shaft 97 is thus brought to a stop at a predetermined position depending upon the particular stop member which has

entered the alignment in the disks. The typewheel shaft 97 is supported from the framework in bearings 98' and 99 and slidably keyed thereto is a friction drive clutch member 101. A helical spring 102 interposed between the shoulders on the collar 103 and the clutch 101, frictionally engages the clutch member with a typewheel 104, the extension 105 of which carries the stop arm 98. The typewheel shaft 97 carrying on its other end a spiral gear 106 rotatable therewith and meshing with worm 107 on the main drive shaft 34, normally tends to rotate but is latched against rotation while the seeker stop arm 98 engages one of the stop pins 93 on the circumferential surface. As soon, however, as the stop pin 93 is forced out of engagement with the stop arm 98 the typewheel 104 starts rotating and continues until the stop arm 98 again reaches a stop pin 93 which has dropped into the aligned notches due to the new setting of the selector disks 87 and the typewheel is again brought to a stop.

To prevent rebound of the stop arm attached to the typewheel when the former strikes the selected stop pin 93, a latching spring 108 is provided, Figs. 15 and 16, secured to the stop arm 98. Latching spring 108 which is normally substantially in alignment with stop arm 98 is cammed or pressed outwardly and rides over the front end of the selected stop pin 93 when the latter is reached, and latches in front of it by its own spring tension when the arm 98 comes to a stop. When a new stop position is selected, the stop pin 93 engaging the stop arm 98 is forced out of the aligned slots and out of the path of the stop arm which thereupon rotates to the new selected position. By this arrangement, as soon as the typewheel is brought to a stop, the member 108 by engaging the opposite side of the stop pin 93 locks the typewheel and prevents any chattering or rebound. A modified form of such a stop is shown in Figure 17 in which the well known form of bicycle coaster brake is employed. The typewheel shaft and clutch member 101 are similar to that described in connection with Figure 1, and are accordingly not described again. Similar characters are employed for like parts in this modification. As shown in Figure 18, the rollers 111 are set in wedge 55 shape openings 112 between wedge member 113 and the ring 114. The typewheel 104 as in Figure 1, carries the stop arm 98 on its extension 105. Member 113 is secured by screws 115 to the member 116 which carries a lever 117 at its end. Lever 117, as is shown in Figure 17, is rocked with the typewheel hammer in a manner to be described. When the typewheel is brought to a stop by arm 98, the printing operation starts and member 116 is rotated wedging the rollers

111 and locking the typewheel in its stop position to prevent rebound.

The speed of rotation of the typewheel is so timed that one complete revolution will take place in the period covered from the stop signal at the end of the preceding code to approximately the fourth or fifth impulse in the succeeding code series, employing as will now be clear, substantially the entire signaling period for the printing operation. As was described above, following the complete receipt of the code, the settings of the wishbone selectors 43 are transferred to the selector disks 87 through transfer selectors 55. Selector disks 87 are positioned in accordance with this code. Immediately, upon the movement of the disks to a new setting the stop pin 93 in an aligned slot is cammed out and the typewheel is released to rotate while the succeeding code is being received on the wishbone selectors 43. By automatically releasing the typewheel as soon as a new code is set up, the maximum possible time is allotted for rotation thereof increasing the speed of operation.

Printing operations as are now about to be described in detail may then substantially cover a period from the mid-portion of the fourth impulse until the stop interval when again as in the previous case, a new code which has not been set up on the wishbone selectors is transferred to the selector disks 87 and the typewheel shaft is again released for the new selection.

Two modified forms for selecting the row of type on the typewheel to be operated are disclosed in Figures 10, 11 and 14. In Figure 10, a sixth wishbone selector 43 is mounted with the other selectors on pin 44 and rocked thereabout by an individual finger on the shaft 11 in a manner described in detail with respect to the other selectors. A horizontally extending member 122 carried by the selector at its extremity is pivoted on a pin 123 by means of sleeve 124 for rotation therewith. The portion 125 of member 122 is positioned between the shoulders of the impact members 126 and 127 and which are moved thereby either to the right or left to engage either of the printer hammers in accordance with the position of the selecting lever 43, which in turn is positioned in accordance with the sixth impulse in the code. As will appear hereinafter one of the impact members rendered operative in this manner to engage its associated printing hammer is thus selected, a direct connection being provided between the sixth selecting lever 43, and the impact rollers.

As shown in Figures 11 and 14, a modified form of the arrangement is disclosed in which the printing hammers are selected through the medium of the transfer mechanism instead of directly by the selecting lever as described above. In this case, the

extension 122 of the selecting lever 43 is omitted and the transfer lever 55' is added. Each time the transfer mechanism 55' operates as described above bringing the group 5 of transfer levers, including the lever 128 against the wishbone selectors 43, a projection on the selector lever 43 strikes a projection of the lever 128 rocking it either up or down and moving the rollers 126 and 10 127 by means of the connecting lever 128. One of the impact rollers 126 and 127 are thus positioned beneath the typewheel hammer which it, therefore, pushes into engagement with its associated typewheel as described hereinafter.

Secured to the end of the typewheel shaft 103, and rotatable therewith is a typewheel 104 as shown in Figure 8, provided with two rows of type characters respectively 20 one of numerals and the other of letters arranged about the periphery. The typewheel is mounted on an extension sleeve 105 and arranged to rotate with the typewheel shaft 103 through clutch 101. As the typewheel rotates, the characters on the periphery are sequentially brought opposite the printing hammers 131 and 132 individual to each row of characters. The printing hammers are pivotally mounted on pins 133 30 carried in the slot of a pivoted arm 134 which have projections 135 on their lower side. Positioned just below the projections 135 and in co-operative relation therewith are impact members 136 and 137 similar to impact members 126 and 127, Figure 10, 35 slidably mounted on pin 138 in frame 139. One of these is positioned in operative relation with its associated hammer as described above. The frame 139 is carried by 40 a printing arm 141 pivoted at 142, mounted on and rotatable with a spindle 143. The spindle 143 has secured thereto by means of set screw 144, a lever arm 145 provided at its extremity with a follower 146 riding on 45 cam 64 on the outer shaft 65. At a predetermined interval in the rotation of the outer shaft following the setting of the selectors the lever 145 is rocked to rotate spindle 143 which in turn rocks the lever 50 arm 141 about its pivot 142 and forces the selected impact member 136 or 137 to move the associated print hammer 131 or 132 against the typewheel 104.

A tape 150 moves between the printing 55 hammers 131 and 132 and the typewheel 104. Carried by the pin 143 is a lever 151 carrying in its end a pawl 152 which engages the teeth of a ratchet wheel 153 mounted on the same pin as and rotatable with 60 feed wheel 154. As the lever arm 151 is rocked about pin 143 the pawl 152 engages the successive teeth of the ratchet wheel 153 while a jockey roller 155 carried on the arm 156 pivoted at 157 and held in engagement 65 with the ratchet wheel by a spring 158 pre-

vents the ratchet wheel 153 from moving in a clockwise direction. A pressure roller 159 carried in a lever 161 mounted in a pin 162 has secured thereto a helical spring 163 the other end of which is secured to the frame work. The pressure roller 159 forces the tape against the feed roller. As shown in the diagram, feeding of the paper starts immediately after the selected character is printed. An ink pad 164 supported from the frame brackets 165 presses against the periphery of the typewheel, as shown.

It will be recalled that one of the features of the invention is to control the motor drive for the printer by the selecting apparatus. This arrangement comprises lever controlled contacts which are included in the motor circuit. As shown in Figures 12 and 13, a pair of spring pressed contacts 170 and 171 are normally held in disengagement by a lever arm 172. Lever arm 172 is pivoted at 173 and locked in the position shown under shoulder 174 of the lever 175. The lever 175 pivoted at 176 is held in operated position by the helical spring 177. To close the contacts in starting the motor, the armature 7 of the receiver magnet 3 is operated in response to the start impulse. As the armature 7 moves to the right it rocks lever 175 about its pivot 176 against spring 177 and removes the shoulder 174 from lever 172. Lever 172 is unlatched permitting the contacts 170 and 171 to close. As will be understood, these contacts are in the motor circuit.

To stop the motor a code combination of impulses is sent over the line which selects the stop pin 178. Stop pin 178 is operated in the manner described above for other selecting operations and when operated rocks the bell crank 179 about its pivot 180, to bring the lever 172 in the path of a printing hammer. This when operated, as described above, rocks the lever 172 so that it will be latched by the lever 175.

It will be apparent to those skilled in the art, that a type bar printer can be controlled by my overlap arrangement, as well as the typewheel printer which I have chosen to illustrate my invention. Other variations of my invention will be apparent to those skilled in the art, and may be made without departing from the spirit of the invention. Accordingly, what is desired to be secured by Letters Patent and claimed as new is:

1. In a printing telegraph receiver, a motor, a normally open circuit therefor, selector apparatus, an electromagnet responsive to received code combinations of impulse conditions for operating said selector apparatus, said magnet being responsive to the first received impulse for closing said motor circuit and said selector apparatus being operative in response to a predetermined code combination of conditions for opening

- said motor circuit and means operative following the opening of said motor circuit for locking said circuit open.
2. In a printing telegraph receiver, a motor, a normally open circuit therefor, selector apparatus, an electromagnet responsive to received code combinations of impulses for operating said selector apparatus, said electromagnet being responsive to the first received impulse of the code for closing said motor circuit, said selector apparatus being responsive to a predetermined code for opening said motor circuit and means for locking said circuit in open condition.
3. In a printing telegraph receiver, printing mechanism responsive to received code combinations of conditions, a motor, means including said receiver responsive to received code combinations of impulses for selectively controlling the energizing circuit of said motor and mechanical locking means for maintaining the motor circuit in the condition determined by said code.
4. In a printing telegraph receiver, a motor therefor, selector apparatus responsive to received code combinations of impulses for selectively operating said printing telegraph receiver and means controlled by said selector apparatus for selectively controlling said motor circuit and means for locking said motor circuit in operated condition.
5. In a printing telegraph receiver, an electric motor, selector apparatus responsive to received code combinations of impulses for selectively operating said receiver, means responsive to a predetermined operation of said selector for selectively operating said motor and means for locking said motor circuit.
6. In a printing telegraph receiver, a first selector responsive to received code combinations of impulses, said selector having no normal position, second selectors and means operative following the operation of said first selector for transferring the settings thereof to said second selectors.
7. In a printing telegraph receiver, a first selector responsive to received code combinations of impulses, said selector comprising a plurality of members having no normal positions, a second set of selectors selectively operated by said first selectors, printing apparatus selectively operated by said second selectors, said first selectors being responsive to succeeding code combinations of impulses while said printing operation is taking place.
8. In a printing telegraph receiver, a first set of selectors each having a marking and spacing position, said selectors being operated to either position, responsive to a received code combination of impulses, a second set of selectors, transfer mechanism operative following the setting of said first
- selectors for transferring said setting to said second selectors, printing apparatus selectively controlled by said second selectors while said first selectors are responsive to a succeeding code combination of impulses, said first selectors being arranged to remain in position independently of any latch devices.
9. In a printing telegraph receiver, a first set of pivoted selectors comprising a plurality of members each having a marking and spacing position but no normal position and arranged to be positioned and remain in the position set in response to a received code combination of impulses, a second set of selectors and means operative following the setting of said first selectors for transferring said setting to said second set of selectors, said first selectors remaining in operated position until operated to a different position by a succeeding code.
10. In a printing telegraph receiver, a first set of selectors, comprising a plurality of pivoted selector bars having no normal positions, a selector disk individual to each of said selectors, transfer mechanism, means responsive to received code combinations of impulses for selectively operating said first selector bars, said transfer mechanism being thereafter operative to transfer said operations to said selector disks and printing apparatus operated by said selector disks while said selector bars are operated in response to a succeeding code combination of impulses.
11. In a printing telegraph receiver, a typewheel, a rotatable shaft carrying said typewheel, a stop arm carried by said shaft, selector mechanism co-operating with said stop arm to bring said typewheel to a stop at a selected position and means cooperating with said stop arm operative following the stopping of said typewheel for preventing said typewheel from chattering.
12. In a printing telegraph receiver, a rotatable typewheel, selector apparatus responsive to received code combinations of impulses for selectively operating said typewheel to stop position and means operative following the positioning of said typewheel for preventing rebound of said typewheel.
13. In a printing telegraph receiver, a typewheel, means for rotating said typewheel, a stop mechanism for selectively bringing said typewheel to a stop for a printing operation and a spring operating said stop mechanism for preventing rebound of said typewheel.
14. In a printing telegraph receiver, a rotatable typewheel, a plurality of circumferentially placed stop pins, a stop arm rotating with said typewheel, and arranged to engage a selected one of said stop pins and a spring member carried by said stop

- arm for engaging said stop pin to prevent rebound of said stop arm.
15. In a printing telegraph receiver, a rotatable typewheel, a plurality of circumferentially placed stop pins, a stop arm carried by said typewheel for engaging a selected one of said stop pins, and means operative following the engagement of said stop arm with a stop pin for locking said stop arm against rebound. 70
16. In a printing telegraph receiver, a first set of selectors responsive to received code combinations of impulses, a second set of selectors, transfer mechanism operative following the setting of said first selectors for transferring said setting to said second selectors, a plurality of type hammers, one of said first selectors being operated in response to an impulse of said code for selecting one of said hammers, said selector being operative simultaneously with the transfer of said selecting operations for conditioning one of said hammers for operation. 75
17. In a printing telegraph receiver, a first selector responsive to received code combinations of impulses, a second selector, a source of mechanical power for setting said first selectors in accordance with said code combinations of impulses, a drive shaft normally disconnected from said power source, a second set of transfer selectors and printing means controlled from said drive shaft and means operative following the setting of said first selectors for connecting said drive shaft to said source of power to operate said transfer and printing means. 80
18. In a printing telegraph receiver, first selectors, a shaft, a source of mechanical power supplied through said shaft for selectively operating said first selectors in accordance with a received code combination of impulses, a transfer mechanism, a printing mechanism, a second shaft for operating said transfer mechanism and printing mechanism said second shaft being normally disconnected from said source of power and means controlled from said first shaft for connecting said second shaft to said source of power to operate said mechanism. 85
19. In a printing telegraph receiver, a selector mechanism, a receiver magnet having an armature responsive to received code combinations of impulses for selectively operating said selector mechanism and means operative at predetermined intervals of each signaling period for locking the armature of said magnet against operation and in its operated position. 90
20. In a printing telegraph receiver, a selector mechanism, a receiver magnet including an armature responsive to received code combinations of impulses for actuating said selector mechanism, means operating at predetermined periods of each signaling period for locking the armature of the mag- 95
- net in operated position and means including said selector mechanism operative following each operation thereof for locking said selector against operation during the remainder of the impulse period. 100
21. In a printing telegraph receiver, a first set of selectors having no normal position and responsive to received code combinations of conditions, a second set of selectors, transfer mechanism operative following the setting of said first selectors for transferring the setting of said first selectors to said second selectors, a plurality of type hammers, operating mechanism therefor connected to one of said selectors for conditioning one of said printing hammers for operation in accordance with the code impulse condition which operated said selector, said operation occurring simultaneously with the transfer of said selecting apparatus from said first set of selectors to said second selectors. 105
22. In a printing telegraph receiver, a first set of selectors having no normal position and responsive to received code combinations of impulse conditions, a second set of selectors, a source of mechanical power for setting said first selectors in accordance with received code combinations of impulse conditions, means for transferring the setting of said first selectors to said second selectors, a plurality of printing hammers, operating means for said printing hammers in operative relation with one of said first selectors and directly operated thereby in accordance with an impulse of said code for conditioning one of said printing hammers for operation and means controlled by said second selectors for selecting one of a series of printing characters for printing operation by said hammers. 110
23. In a printing telegraph receiver, a first set of selectors having no normal position and responsive to received code combinations of conditions, a second set of selectors, transfer mechanism operative following the setting of said first selectors for transferring said setting to said second selectors, printing apparatus variably conditioned for printing operations in accordance with the setting of said second selectors, a plurality of type hammers, control means for said type hammers, a selector operated in response to an added impulse in addition to said code impulses, said selector being directly connected to said control means for variably operating said control means to condition one or the other of said printing hammers for operation against said printing mechanism in accordance with the setting of said selector. 115
24. In a printing telegraph receiver, a plurality of u-shaped selectors each having projections on either leg thereof and means responsive to received code combinations of impulse conditions and cooperating with 120
- 125
- 130

said projections for rocking said selectors. 25. In a printing telegraph receiver, a plurality of pivoted u-shaped selectors each having lug extensions on either leg thereof and means responsive to received code combinations of impulse conditions and cooperating with said lug extensions for rocking said pivoted selectors.

26. In a printing telegraph receiver, a plurality of u-shaped selectors having cam surfaces on either leg thereof, and a pin barrel selector shaft responsive to received code combinations of impulse conditions for engaging said cam surfaces, for rocking said selectors in accordance with received code combinations of impulses.

27. In a printing telegraph receiver, a plurality of u-shaped pivoted selector levers having no normal position and means responsive to received code combinations of impulse conditions for rocking said selectors in accordance with said received code to a marking or spacing position.

28. In a printing telegraph receiver, a plurality of pivoted u-shaped selectors having no normal position, an extension on each of the legs of said selectors, and a shaft having an individual pin for each of said selectors and arranged to be in operative relation with its associated selector when the code impulse condition therefor is received for rocking said selector to marking or spacing position in accordance with the received code condition.

29. In a printing telegraph receiver, a motor, means including said receiver responsive to a received code combination of impulses for selectively controlling the energizing circuit of said motor, mechanical locking means for maintaining the motor circuit in the condition determined by said code, a set of selectors, transfer mechanism for operating said selectors in accordance with the operation of said first means and typewheel printing mechanism variably operated by said selectors.

30. In a printing telegraph receiver, a first set of selectors, responsive to received code combinations of conditions, said selectors comprising a plurality of members having no normal positions, a motor and an energizing circuit therefor, said selectors operating in response to a predetermined impulse condition for closing said motor circuit, means for maintaining said motor circuit closed thereafter, a second set of selectors, means for transferring the setting of said first selectors to said second selectors and a printing mechanism operated in accordance with the setting of said second selectors.

31. In a printing telegraph receiver, a first set of selectors each having a marking and spacing position, said selectors being operated to either position in accordance

with received code combinations of conditions, a motor for said receiver, said motor being started into operation in response to the first impulse received, a second set of selectors, transfer mechanism operative following the setting of said first selectors for transferring the setting to said second selectors, printing apparatus selectively operated by said second selectors while said first selectors are responsive to a succeeding code combination of impulses, said first selectors being arranged to remain in position independently of any latching devices.

32. In a printing telegraph receiver, a first set of selectors each having a marking and spacing position but no normal position, said selectors being operated to either position responsive to received combinations of conditions, a motor responsive to the operation of said selectors for controlling the operation of said receiver, a second set of selectors, transfer mechanism operative following the setting of said first selectors for transferring the setting to said second selectors and printing mechanism selectively controlled by said second selectors.

33. In a printing telegraph receiver, a motor for driving said receiver, said motor being normally in an open circuit, a first set of selectors each having a marking and spacing position but no normal position, arranged to be positioned and to thereafter independently remain in position in accordance with received combinations of conditions, means controlled by the first impulse of a code for closing said motor circuit to start said receiver into operation, a second set of selectors, means operative following the setting of said first selectors for transferring said setting to said second selectors, said first selectors remaining in operated position until operated to a different position by a succeeding code and printing mechanism variably operated in accordance with the setting of said second selectors.

34. In a printing telegraph receiver, a motor for driving said receiver, said motor being normally in an open circuit, a first set of u-shaped selectors each having a marking and spacing position but no normal position, arranged to be positioned in accordance with received combinations of conditions, means controlled by the first impulse of said code for closing said motor circuit to start said receiver into operation, a second set of selectors, means operative following the setting of said first selectors for transferring said setting to said second selectors, said first selectors remaining in operated position until operated to a different position by a succeeding code, printing mechanism variably operated in accordance with the setting of said second selectors, and means controlled by said selectors for reopening said motor circuit.

35. In a printing telegraph receiver, a set of u-shaped pivoted selectors each having a marking and spacing position, said selectors being operated to either position responsive to received combinations of impulses, a second set of selectors, transfer mechanism operated following the setting of said first selectors for transferring the setting to said second selectors, and printing apparatus selectively controlled by said second selectors while said first selectors are responsive to the succeeding code combinations of impulses said first selectors being arranged to remain in position independently of any latch devices. 5
36. In a printing telegraph receiver, a first set of pivoted u-shaped selectors, each having a marking and spacing position but no normal position, and arranged in position and to remain in position in response to a received code combination of conditions, a second set of selectors and means operative following the setting of the first selectors for transferring said setting to said 10 second selectors. 20
37. In a printing telegraph receiver, a first set of pivoted u-shaped selectors having no normal position, a selector disk individual to each of said selectors, transfer mechanism, means responsive to received code combinations of impulse conditions for selectively operating said first selectors, said transfer mechanism being thereafter operative to transfer said operation to said selector disks and printing apparatus operated by said selector disks while said selectors are operated in response to succeeding code 25 combinations of impulses. 35
38. In a printing telegraph receiver, a first set of selectors having no normal position, a motor, means responsive to received code combinations of impulse conditions for variably operating said selectors, means controlled by said selectors for variably 40 controlling the operation of said motor, a selector disk individual to each of said selectors, transfer mechanism, means responsive to received code combinations of impulses for selectively operating said first 45 selectors, said transfer mechanism transferring the setting of said first selectors to said selector disks, said first selector operating in response to a succeeding code combination of conditions thereafter. 50
39. In a printing telegraph receiver, a first set of pivoted u-shaped selectors, having no normal position, a motor, means responsive to received code combinations of impulse conditions for variably operating 55 said selectors, means controlled by said selectors for variably controlling the operation of said motor, a selector disk individual to each of said selectors, transfer mechanism, means responsive to received code 60 combinations of impulses for selectively op- erating said first selectors, said transfer mechanism being operative to set said disks in accordance with the operation of said first 65 selectors and printing apparatus controlled by said selector disks while said first 70 selectors are operated in response to a succeeding code combination of impulse conditions. 75
40. In a printing telegraph receiver, a first set of selectors comprising a plurality of pivoted selector bars having no normal position, a selector disk individual to each of said selector bars, transfer mechanism, means responsive to received code combinations of impulses for selectively operating said selector bars, said transfer mechanism being thereafter operative to transfer said operation to said selector disks, a printing rotatable typewheel, a plurality of circumferentially positioned stop pins selectively operated by said selector disks, a stop arm rotating with said typewheel and arranged to engage a selected one of said stop pins and a spring member carried by said stop arm for engaging said stop pins to prevent rebound of said stop arm. 80 85
41. In a printing telegraph receiver, a first set of selectors having no normal position, a second set of selectors individual to each of said first selectors, transfer mechanism, means responsive to received code combinations of impulse conditions for selectively operating said first selectors, said transfer mechanism being thereafter operated to transfer said operation of said first 90 selectors to said second selectors, a rotatable typewheel, a plurality of circumferentially placed stop pins selectively operated by said 95 selectors, a stop arm rotating with said typewheel and arranged to engage said selected ones of said stop pins and a spring member carried by said stop arm for engaging said stop pin to prevent rebound of said stop arm. 100 105
42. In a printing telegraph receiver, a first set of selectors, a second set of selectors, means for operating said first selectors in accordance with received code combinations of impulses, transfer mechanism for transferring the setting of said first selectors to said second selectors, a rotatable type wheel selectively operated to a stop position in accordance with the operation of said second 110 115 selectors and means operative following the positioning of said typewheel for preventing rebound thereof. 120
43. In a printing telegraph receiver, a plurality of selectors having no normal position, means responsive to received code combinations of impulses for variably operating said selectors, a second set of selectors, transfer mechanism for setting said second selectors in accordance to the operation of said first 125 selectors, a typewheel, means for rotating said typewheel, a stop arm carried with said type wheel, means controlled by said 130

second selectors for engaging said stop arm for bringing said stop arm to a stop in accordance with the operation of said second selectors and means operative following the stopping of said typewheel for preventing rebound thereof.

44. In a printing telegraph receiver, a plurality of selectors having no normal position, means responsive to received code combinations of impulses for variably operating said selectors, a second set of selectors, transfer mechanism for setting said second selectors in accordance with the operation of said first selectors, a typewheel, means for rotating said typewheel, a stop arm carried with said typewheel, circumferentially positioned stop pins controlled by said second selectors for engaging said stop arm for bringing said stop arm to a stop in accordance with the operation of said second selectors and a spring member carried by said stop pin for engaging said stop arm to prevent rebound of said stop arm.

45. In a printing telegraph receiver, a first set of selectors, a receiver magnet having an armature responsive to received code combinations of conditions for selectively operating said first set of selectors, means operative at a predetermined interval in each signal interval for locking the armature of the magnet against operation in its operated position, a second set of selectors, transfer mechanism, means for transferring the setting of said first selectors to said second selectors and printing mechanism variably operated by said second selectors.

46. In a printing telegraph receiver, a first set of u-shaped pivoted selectors having no normal position, a receiver magnet having an armature responsive to received code combinations of conditions for selectively operating said first set of selectors, means operative at a predetermined interval of each signaling interval for locking the armature of the magnet against operation in its operated position, a second set of selectors, transfer mechanism, means for transferring the setting of said first selectors to said second selectors and printing mechanism variably operated by said second selectors.

47. In a printing telegraph receiver, a plurality of selectors having no normal position sequentially operated in accordance with received code combinations of signaling conditions, a plurality of typewheels, means controlled by said selectors for variably operating said typewheels, a printing hammer individual to each typewheel, and a selector responsive to an additional impulse for selectively operating one of the printing hammers against the selected character on said typewheel.

48. In a printing telegraph receiver, a plurality of u-shaped pivoted selectors hav-

ing no normal position, a plurality of typewheels, means controlled by said selectors for variably operating said typewheels to a stop position, a printing hammer individual to each of said typewheels, and a u-shaped selector having no normal position and operated in response to a predetermined impulse condition for selectively selecting one of said printing hammers for operation against its associated typewheel.

49. In a printing telegraph receiver, a plurality of typewheels, a plurality of selectors having no normal position, means responsive to received code combinations of impulse conditions for variably operating said selectors sequentially, means controlled by said selectors for rotating said typewheels to a predetermined position and a further selector responsive to an additional impulse for determining which of said typewheels is operated to print each character.

50. In a printing telegraph receiver, a plurality of typewheels, a motor for driving said typewheels, selectors having no normal positions and responsive to received code combinations of conditions for variably conditioning said typewheels for operation, a further selector responsive to a further impulse for selecting which of said typewheels is to be operated, and means controlled by the first of said impulses for starting the motor into operation.

51. In a printing telegraph receiver, a plurality of typewheels, a motor for driving said typewheels, selectors having no normal positions and responsive to received code combinations of conditions for variably conditioning said typewheels for operation, a further selector responsive to a further impulse for selecting which of said typewheels is to be operated, means controlled by the first of said impulses for starting the motor into operation and means responsive to variable operation of said selectors for stopping the operation of said motor.

52. In a printing telegraph receiver, a plurality of type-wheels, a motor for driving said typewheels, u-shaped pivoted selectors having no normal position and responsive to received code combinations of conditions for variably conditioning said type-wheels for operation and a further selector responsive to a further impulse for selecting which of said typewheels is to be operated, means controlled by the first of said impulses for starting the motor into operation and means responsive to variable operation of said selectors for stopping the operation of said motor.

53. In a printing telegraph receiver, a plurality of selectors having no normal position sequentially operated in accordance with received code combinations of signaling conditions, a plurality of typewheels, a printing hammer for each typewheel, means

- controlled by said selectors for variably operating said typewheels and a selector responsive to an additional impulse for selectively rendering one of the printing hammers operative to print the selected character.
54. In a printing telegraph receiver, a plurality of u-shaped pivoted selectors having no normal position, a plurality of typewheels, means controlled by said selectors for variably operating said typewheels to a stop position and a u-shaped selector having no normal position and operated in response to a predetermined impulse condition for selectively conditioning one of said typewheels for operation.
55. In a printing telegraph receiver, a first set of u-shaped selectors responsive to received code combinations of conditions, a second set of selectors, transfer mechanism operative following the setting of said first selectors for transferring the setting of said first selectors to said second selectors, means controlled by said second selectors for selecting a character to be printed and means controlled by one of said selectors for printing the selected character in offset position.
56. In a printing telegraph receiver, a first set of u-shaped selectors responsive to received code combinations of impulse conditions, a second set of selectors, a source of mechanical power for setting said first selectors in accordance with received code combinations of impulse conditions, means for transferring the setting of said first selectors to said second selectors, means controlled by said second selectors for selecting a character for printing and means controlled by one of said first selectors for printing the selected character in offset position.
57. In a printing telegraph receiver, a motor having an energizing circuit; means including said receiver responsive to received code combinations of signaling conditions for selectively controlling said energizing circuit; means for variably operating said printing telegraph receiver in accordance with received code combinations of signaling conditions to print characters; and means whereby certain of said characters are printed in offset relation with respect to others of said characters.
58. In a printing telegraph receiver, a motor having an energizing circuit; means including said receiver responsive to received code combinations of signaling conditions for selectively controlling said energizing circuit of said motor; means for variably operating said printing telegraph receiver in accordance with received code combinations of signaling conditions to print characters; and means whereby certain of said characters are printed in offset relation with respect to others of said characters in accordance with the character of an impulse condition accompanying each code combination.
59. In a printing telegraph receiver; a motor, a circuit therefor; selector mechanism responsive to received code combinations of signaling conditions for selectively operating said printing telegraph receiver to print characters; means controlled by said selector apparatus for selectively controlling said motor circuit; and means whereby said printer prints characters in offset relation with respect to others of said characters in accordance with an impulse condition accompanying each code combination of conditions.
60. In a printing telegraph receiver; a motor; a normally open circuit therefor; selector apparatus; an electromagnet responsive to received code combinations of signaling conditions for operating said selector apparatus; means whereby said selector apparatus variably operates said printing telegraph receiver to print characters in accordance with said received code combinations; means whereby said telegraph receiver prints certain of said characters in offset relation with respect to other characters in accordance with a control condition accompanying each code combination; means whereby said magnet operating in response to the first received condition of a code combination closes said motor circuit; and means controlled by said selector apparatus in accordance with a predetermined code combination of signaling conditions for opening said motor circuit.
61. In a printing telegraph receiver having characters in letters and figures case position; a motor; means responsive to received code combinations of signaling conditions for selectively printing said characters; means controlled by a control condition accompanying each code combination for determining whether a character in the figures or letters case is to be printed; and means responsive to received code combinations of conditions for selectively controlling the energizing circuit of said motor.
62. In a printing telegraph receiver; a plurality of selectors having no normal positions; means responsive to received code combinations of impulse conditions for sequentially operating said selectors; a second set of selectors variably operated simultaneously in accordance with the operation of the first set of selectors; a plurality of characters in normal and shift position; means controlled by said second selectors for selecting a character in each position for operation; and means responsive to a control condition accompanying each code combination for selecting one of said selected characters for printing.
63. In a printing telegraph receiver; a plurality of characters; a plurality of se-

lectors having no normal positions; means for sequentially operating said selectors selectively in accordance with received code combinations of conditions; and means controlled by a condition accompanying each code combination for recording certain of said characters in offset relation with respect to others of said other characters.

64. In a selecting device, a series of 10 notched selector disks, operated in varying permutations, a plurality of circumferentially positioned selectable members, each of said members provided with a group of anti-friction rollers, each roller in said group individual to a selector disk, one permutation of said disks adapted to align a series of notches to permit the rollers on one of said members to enter into the notched space, means to reoperate said disks in accordance 20 with another permutation whereby said operated member is cammed out therefrom.

In testimony whereof I affix my signature.
EDWARD E. KLEINSCHMIDT.
